UNITED STATES PATENT OFFICE

2,464,208

EXPANSIBLE CHAMBER FLUID MOTOR OR
PUMP

Calvin M. Bolster, United States Navy

Application October 31, 1945, Serial No. 625,931

6 Claims. (Cl. 103—116)

(Granted under the act of March 3, 1883, as
amended April 30, 1928; 370 O. G. 757)

1

This invention relates to an improved expandable chamber fluid motor or pump.

An object of this invention is to provide a fluid device having a plurality of expandable chambers, several of which are always filling while the remainder are exhausting, and each of the said chambers fills and exhausts once during each revolution of the said device.

A further object of this invention is to provide a fluid motor that will give a high torque load.

A still further object of this invention is to provide a fluid motor that will develop torque the instant pressure is applied to the motor and which will develop its maximum torque almost instantly.

A yet further object of this invention is to provide a fluid pump that requires a minimum torque load to move a given volume of fluid.

Another object of this invention is to provide a fluid pump that will move its maximum volume of fluid almost instantly upon applying torque to the said pump.

Another object of this invention is to provide a fluid device that has a very large volumetric efficiency.

A further object of this invention is to provide a fluid pump, that when used as a compressor, is capable of handling large volumes at high pressures.

Another object of this invention is to provide a fluid pump or compressor that is capable of handling large volumes of compressible fluids due to the cooling effect of the incoming fluid.

Other objects and advantages of this invention will become apparent as the discussion proceeds, and is considered in connection with the accompanying drawings, wherein like characters of reference designate like parts in the several views, and wherein:

Fig. 1 is a vertical cross-section view of the device embodied in this invention showing the position of the inlet and outlet ports in relation to the expandable chambers, taken on the lines 1—1 of Fig. 2.

Fig. 2 is a longitudinal cross-section view of the device embodied in this invention taken on the line 2—2 of Fig. 1 showing the position of the inlet and outlet ports in relation to the housing and crank shaft, and

Fig. 3 is a perspective view of both the curved and straight vanes of the device embodied by this invention, showing the hinge bearings.

Referring now to the drawings, wherein for the purpose of illustration, is shown a preferred embodiment of this invention and wherein like numerals designate like parts throughout, the nu-

2

merals 8 designates a stand or base carrying a cylindrical housing or case 9 having inner walls 10 which form a cylindrical chamber 11. Circular end plates 12 affixed to the ends of the housing 9 by bolts 13 complete the closure of the chamber 11. Annular fluid passages 14, provided in the end plates 12, as shown, admit fluid into the chamber 11. Continuous annular recesses 15 located near each end of the cylinder 9, as shown, are provided in the inner walls 10 of the cylinder 9 and are in open communication with the chamber 11 to permit escapement of fluid from the cylindrical chamber 11 through suitable apertures 16. Depending arms 17 are affixed to the inner walls 10 of the cylinder 9 in any conventional manner, as by welding or the like, or may, if desired, be cast integral with the cylinder housing, and are located midway the said cylinder between the annular recesses 15. Carried upon the lower end of the depending arms 17 are one-half of a hinge bearing 18. Curved vanes 19 extending laterally the chamber 11 are pivotally hinged at one end to the hinge bearing 18 by means of a second half of a hinge bearing 20. A pin 21 interconnects the hinge bearings 18 and 20. A second hinge bearing half 22 is provided on the opposite end of the vane 19 and hinges the said vane to a corresponding second half of a hinge bearing 23, provided on a flat vane 24. The hinge bearings 22 and 23 are held together by a pin 22a. The said flat vane 24 extends laterally the length of the chamber 11, the same as the curved vane 19. The curved vane 19 and the flat vane 24, when assembled form one wall of an expandable chamber. A small clearance is provided between the bearings 18 and 20 and also between the bearings 22 and 23, as shown to enable an effective pressure seal to be formed between the bearings. The number of curved vanes 19 and flat vanes 24 are shown, for the purpose of illustration, to be five, but it is to be understood that the number of such vanes can be varied without departing from the spirit of this invention; however, it is recommended that the number be decreased to not less than three.

Two wrist-arms 25 are provided on each of the flat vanes 24, as shown in Fig. 3, and are adapted to carry a crank pin 26. A bushing 27 inserted between the wrists 25, and the crank pin 26 serves as a friction bearing. A small clearance between the flat vane 24 and the bushing 27 provides an effective pressure seal. The wrist-arms 25 on each of the flat vanes 24 are in staggered relation to permit assembly on the crank pin. Bushings or separators in the form of space

washers may be provided to take up any clearance between adjacent wrist-arms to form friction bearings and pressure-type close-clearance seals. The crank pin 26 is splined at each end to receive identical circular end plates 28. The said circular end plates rotate within the chamber 11. Each plate 28 carries a shaft 29 rotatably supported by pressure-sealed bearings 30, either of the ball or rotor type, provided in the end plates 12 of the housing; the bearings being effectively pressure-sealed by reason of the close clearances at 41 and 42 as shown. On one or both of the shafts 29 is a pulley or other suitable power take-off mechanism 31, keyed thereto in any suitable manner. More effective pressure seals may be obtained at the various bearings referred to above by the use of well known wiper strips such as shown for example at 43, slidably mounted in a corresponding slot and biased to close the clearance between the bearing surfaces. The present invention however is not concerned with any specific type of pressure sealing means for any of the clearances referred to.

In each of the circular end plates, and rotating therewith, is an inlet port 32, in open communication with an annular channel 33 provided circumferentially in each of the plates 28, as shown; the annular channels 33 in turn are in continuous open communication with the annular fluid passage 14. The intake ports 32 are identical in each end plate and are shaped substantially as shown in Fig. 1. The precise cross-sectional area of the said ports will vary with each motor or pump, but the general configuration, as shown, will remain the same. The leading edge of the inlet port 32 takes the same configuration as the leading face of the curved vane 19 and the bearing 18, as shown by the dotted lines in Fig. 1. The following edge of the said port 32 takes the same configuration as the following face of the curved vane 19 and the bearing 18. The radial length of the said inlet port is equal to the radial distance from the leading edge or face of one of the said curved vanes 19 to the following edge or face of the second next adjacent curved vane 19 as shown in Fig. 1. The actual width of the said port will vary with the variation in structure of vanes 19 and 24 or the cross sectional area of the spaces formed by the said vanes and the position of the crank pin 26.

Cylindrical flanges or lips 34 carried on the outer circumference of the plates 28, as shown, may be affixed thereto in any conventional manner, as by welding or may be cast integral therewith. In each of these said flanges are provided an outlet port 35 as shown in Figs. 1 and 2 in continuous open communication with the annular recesses 15; the radial length of the outlet ports is equal to the radial distance from the center of one of the pins 21 to the center of the next adjacent pin, as shown. The axial width of the said ports varies with the load demand and structural features of each motor or pump.

Structurally, when assembled, five variable volumetric chambers or spaces A, B, C, D and E, as shown in Fig. 1, are formed by the vanes 19 and 24, acting as walls within the chamber 11. When these chambers or spaces, A to E, inclusive, are pressure sealed, each from the other, five separate pressure-sealed variable volumetric chambers or spaces, each having a positive displacement, are formed.

In operation, the circular end plates 28 carrying the crank pin 26, rotate on the shafts 29. The flat and curved vanes 19 and 24, respectively,

being stationarily hinged to the housing 9 at one end, and hinged to the crank pin 26 at the opposite end, oscillate as the crank pin rotates about the axis of the shaft 29, as shown in Fig. 1. This oscillation of the vanes causes the chambers or spaces, formed by the leading surfaces of one set of vanes 19 and 24 and the following surfaces of the adjacent set of vanes 19 and 24 on the other side, and the inner wall 10 of the cylinder 11 on a third side, the crank pin 26 forming the fourth side, to vary in absolute volume; each of these said chambers (A to E, inclusive, in the preferred embodiment of this invention) varying in volumetric size, from the minimum volume of chamber A to the maximum volume of chamber B, as shown in Fig. 1, once during each revolution of the shaft.

The inlet valve 32 begins its opening into chamber A, as chamber A is completely exhausted, and is beginning to expand and closes in chamber B. At this same moment, the outlet port 35 closes in chamber A and opens in chamber B.

When this device is used as a motor, steam or other gas under pressure is carried to the end plates 28 through the annular fluid passage 14 and enters the spaces A to E at the proper time through the inlet ports 32. It is to be here noted that the inlet and outlet ports are disposed in each end of the chamber to relieve both torque on the motor and the thrust on the bearings 30. Steam or gas enters chamber A as it begins to increase in volume, the shape of the inlet port makes the cross-sectional area of the opening of the port almost equal to the cross-sectional area of the chamber A at its smallest volume as soon as the port opens into the said chamber. At this time, the inlet port is also open into both chamber C and D. Energy from the steam or gas acting upon the curved vanes 19, the flat vanes 24 and a small portion of the crank pin urge the cylinder A to expand from its minimum size until it reaches its maximum size equal to that of cylinder B, as shown. As this expanding takes place, the crank pin is caused to rotate about its axis, which in turn causes the drive shaft 29 to rotate about its axis.

The energy from the steam or gas being expended after the cylinder has attained its greatest volume, scavenging takes place from the cylinder 50 through the outlet port 35 as the cylinder decreases in volume. From the foregoing, it will be seen that a device of this nature provides a motor that develops torque almost instantly and that each volumetric space takes in and scavenges its charge once during each revolution of the motor.

It is to be further noted that this device when used as a motor may be converted into a reversible motor by simply reversing the valves which turn the high pressure side of the gas or steam into the recesses 15 and opening the annular fluid passages 14, thereby reversing the direction of the flow of the gas or steam.

When this device is used as a pump or compressor, rotational energy is translated to the vanes 19 and 24, respectively, through the pulley 31, the shaft 29, and the crank pin 26. Fluid is taken into the spaces A to E, inclusive, from the annular fluid passages 14, through the inlet ports 70 32. As the volume of space A is caused to increase in size, fluid is continuously drawn into the said space until it reaches its maximum volume, that is, that volume equal to that of B. The inlet port then closes, and as the space is caused to decrease in volume, the fluid is continuously forced out of

the space through the outlet port 35. In a pump or compressor of this nature large volumes of fluid can be handled easily with a minimum torque load applied to the drive shaft. In event it is desired to use this device as a compressor, the cross-sectional area of the outlet ports may be varied to give the pressure desired.

While the preferred form of this invention has been shown as having the housing stationary and the crankshaft and its assembly rotatable, it is to be understood that the housing can be so constructed as to rotate around a stationary crankshaft and its assembly, without departing from the spirit of this invention.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

The invention described herein may be manufactured and used by or for the Government of the United States of America for governmental purposes without the payment of any royalties thereon or therefor.

What I claim is:

1. In a fluid transmission device comprising a housing, a pressure chamber therein, a crank shaft rotatably coacting with the said housing, and vanes pivotally connected to the said housing and to the crank of said crank shaft forming a plurality of variable volumetric spaces within the said pressure chamber; means having fluid inlet and fluid outlet ports carried by the said crank shaft rotatable in relation to the said pressure chamber, said inlet ports and said outlet ports each being symmetrically arranged with respect to the axial length of said spaces so as to avoid unbalanced and thrust loads on the ends of said chamber and means.

2. In a fluid transmission device comprising a housing, a pressure chamber therein, a crank shaft in rotatable relation to said housing, vanes pivotally connected to the said housing and to the crank of said crank shaft forming a plurality of variable volumetric spaces within the said pressure chamber, and means carried by the said crank shaft adapted to rotate in relation to the said pressure chamber; an inlet port at each end of the aforesaid means adapted to communicate with the said volumetric spaces, each of said inlet ports being characterized by the fact that they are opened due to the rotation of the said crank shaft to a size in cross-sectional area equal to the cross-sectional area of a plurality of the said volumetric spaces, and an exhaust outlet carried by the aforesaid means adjacent each end thereof.

3. A fluid motor comprising a housing, an annular pressure chamber therein, a crank shaft rotatable in said housing having a crank pin substantially the length of said chamber and carrying circular plates adjacent each end of the crank pin, said circular plates being adapted to rotate within the said pressure chamber, inlet apertures in the said circular plates adapted to permit the entrance of fluid under pressure into the said pressure chamber from each end simultaneously, cylindrical flanged portions carried upon the outer periphery of the said circular plates, outlet apertures in the said cylindrical flanged portions adapted to permit the exhaust of fluid symmetrically from the said pressure chamber, vanes pivotally connected to the said housing and to the said crank shaft forming a plurality of variable

volumetric spaces within the said pressure chamber, each volumetric space communicating alternately with the said inlet apertures and with the said outlet apertures during a portion of each revolution of the said crank shaft, and means to introduce fluid under pressure into the said volumetric spaces symmetrically through the said inlet apertures, thereby causing the said vanes to oscillate in said pressure chamber forcing said crank shaft to rotate about its axis distributing the pressure forces so as to prevent unbalance or thrust between said crankshaft and said chamber.

4. A fluid pump comprising a housing, a chamber therein, a crank shaft rotatable in said housing having a crank pin and carrying circular plates adjacent each end of said crank pin, said circular plates being adapted to rotate within the said chamber, an inlet aperture in each of said circular plates adapted to permit the entrance of fluid into the said chamber, cylindrical flanged portions carried upon the symmetrically arranged outer periphery of the said circular plates, outlet apertures in the said cylindrical flanged portions adapted to permit the exhaust of fluid from the said chamber, vanes pivotally connected to the said housing and to the said crank pin forming a plurality of variable volumetric spaces within the said chamber between said plates, each volumetric space communicating alternately with the said inlet aperture and with the said outlet apertures during a portion of each revolution of the said crank shaft, and means for rotating the said crank shaft to cause the said vanes to oscillate within the said chamber, thereby causing fluid introduced into the said volumetric spaces through the said inlet apertures to be discharged through the said outlet apertures at an increased pressure.

5. A fluid motor of the positive displacement type comprising a housing, a pressure cylinder within the said housing, a crank shaft having a crank pin substantially the length of said cylinder and being rotatable in said housing, carrying circular plates adjacent each end of the crank pin serving as crank arms, said circular plates being adapted to rotate within the said pressure cylinder, opposed inlet ports in the said circular plates adapted to permit the entrance of fluid under pressure into the said pressure cylinder, cylindrical flanged portions carried upon the outer periphery of the circular plates, symmetrically arranged outlet ports in the said cylindrical flanged portions adapted to permit the exhaust of fluid from the said pressure cylinder, vanes pivotally connected to the said housing and to the said crank pin provided with pressure sealing means at the pivotal connections and forming a plurality of pressure sealed expandable volumetric spaces axially within the said pressure cylinder between said plates, each volumetric space communicating alternately with the said inlet port and with the said outlet port during a portion of each revolution of the said crank shaft, and means to introduce fluid under pressure into the said volumetric spaces through the said inlet ports, thereby varying the volume of the said spaces by causing the said vanes to oscillate within the said pressure cylinder forcing the said crank shaft to rotate about its axis.

6. A positive displacement device comprising a housing, a pressure chamber within said housing having fluid inlets and outlets, a crank shaft having a crank pin substantially the length of said chamber and being rotatable within the said

pressure chamber, means having symmetrically arranged intake ports and symmetrically arranged exhaust ports mounted upon the said crank shaft rotatable within the said pressure chamber and communicating with the said fluid inlet and the said fluid outlet of the said pressure chamber respectively, a plurality of vanes pivotally connected to the said housing, and to the said crank pin forming a plurality of variable volumetric spaces within the said pressure chamber, said plurality of variable volumetric spaces changing in shape and volume as the crank shaft revolves about its axis, and means provided at said pivotal connections to pressure seal each of said volumetric spaces from adjacent spaces. 15
